[57] CLAIM

The ornamental design for a combined package with candle, as shown and described.

DESCRIPTION

FIG. 1 is a perspective view of a combined package with candle showing my new design;

FIG. 2 is a top plan view thereof;

FIG. 3 is an elevational view thereof;

FIG. 4 is a bottom plan view thereof;

FIG. 5 is a corner elevational view thereof, the other corner elevational views being the same in appearance; and, FIG. 6 is an enlarged sectional view thereof taken along line 6-6 of FIG. 5.
